US00D656501S

(12) **United States Design Patent**
Andre et al.

(10) **Patent No.:** US D656,501 S
(45) **Date of Patent:** ** Mar. 27, 2012

(54) **COMPUTER**

(75) Inventors: **Bartley K. Andre**, Menlo Park, CA (US); **Daniel J. Coster**, San Francisco, CA (US); **Daniele De Iuliis**, San Francisco, CA (US); **Richard P. Howarth**, San Francisco, CA (US); **Jonathan P. Ive**, San Francisco, CA (US); **Steve Jobs**, Palo Alto, CA (US); **Duncan Robert Kerr**, San Francisco, CA (US); **Shin Nishibori**, Portola Valley, CA (US); **Matthew Dean Rohrbach**, San Francisco, CA (US); **Peter Russell-Clarke**, San Francisco, CA (US); **Douglas B. Satzger**, Menlo Park, CA (US); **Calvin Q. Seid**, Palo Alto, CA (US); **Vincent Keane Seid**, legal representative, Los Gatos, CA (US); **Christopher J. Stringer**, Woodside, CA (US); **Eugene Antony Whang**, San Francisco, CA (US); **Rico Zorkendorfer**, San Francisco, CA (US)

(73) Assignee: **Apple Inc.**, Cupertino, CA (US)

(**) Term: **14 Years**

(21) Appl. No.: **29/391,177**

(22) Filed: **May 4, 2011**

Related U.S. Application Data

(60) Continuation of application No. 29/365,139, filed on Jul. 2, 2010, which is a division of application No. 29/289,876, filed on Aug. 2, 2007, now Pat. No. Des. 621,841.

(57) **CLAIM**

The ornamental design for a computer, as shown and described.

DESCRIPTION

FIG. 1 is a front perspective view of a first embodiment of a computer showing our new design;

FIG. 2 is a left side view thereof;

FIG. 3 is a right side view thereof;

FIG. 4 is a top view thereof;

FIG. 5 is a bottom view thereof;

FIG. 6 is a rear perspective view thereof;

FIG. 7 is a front perspective view of a second embodiment thereof;

FIG. 8 is a left side view thereof;

FIG. 9 is a right side view thereof;

FIG. 10 is a top view thereof;

FIG. 11 is a bottom view thereof; and,

FIG. 12 is a rear perspective view thereof.

The broken lines are for the purpose of illustrating portions of the computer and form no part of the claimed design. The black shading on the front of the monitor represents the color black and the dark gray shading on the front of the monitor represents the color gray. The light gray shading on the sides of the monitor represents a metallic-looking surface.

1 Claim, 8 Drawing Sheets
